UNITED STATES PATENT OFFICE

2,459,314

ROCKET LAUNCHER

William V. Goodhue, Ipswich, Mass., assignor to
United Shoe Machinery Corporation, Flemington, N. J., a corporation of New Jersey

Application July 15, 1946, Serial No. 683,674

12 Claims. (Cl. 89—1.7)

1

This invention relates to rocket launching apparatus and is illustrated herein as embodied in a rocket launcher capable of firing a large number of rockets continuously in rapid succession and adapted to be installed on a relatively small vehicle whether waterborne, of the land type, or amphibious.

In the use of one type of apparatus for launching rockets, a number of rockets, representing the capacity of the launcher, may be installed in a series of racks all of which usually are loaded in preparation for an action. If the capacity of this type of launcher is great enough to afford a satisfactorily long period of continuous fire, its overall size would prohibit its use in many types of small craft or vehicles. Moreover, in the use of this type of launcher safety considerations require the firing to be interrupted during the loading period. Consequently, the time required for loading even a small launcher is so great as compared with the time required for firing that the rate of fire is seriously impaired.

In view of the foregoing, the object of the invention is to provide an improved rocket launcher which is so small and compact as to be suitable for outboard installation on a small craft or vehicle and which is also capable of firing rockets continuously by rapid fire until the supply is exhausted, eliminating the dead time formerly entailed by loading.

According to the present invention, a small supply of rockets disposed side-by-side are fed, one-by-one, from one side of the line of fire into firing position and are then fired immediately, the supply being continually replenished at a safe distance from the blast of the fired rockets by a loading crew which passes the rockets to the loading station from the ready boxes of the craft or vehicle.

The above mentioned supply of rockets is contained in the illustrated launcher in a magazine (inclined downwardly outward thereof and also in elevation) through which the rockets are fed by gravity into firing position. The launcher also includes firing means constructed and arranged to be actuated by the falling of a rocket into firing position to fire that rocket.

The rockets are fired electrically after the terminals of a firing circuit are engaged by corresponding terminals on the rockets. Accordingly, it is evident that the rate of fire is limited only by the time required for a rocket to leave the launcher after the firing circuit has been closed plus the time required for the succeeding rocket to drop into firing position from the magazine.

2

Invention is also to be recognized in the provision of means operated by and in synchronism with the falling of a rocket into firing position for closing the firing circuit, whereby the operation of the launcher is made automatic if the usual local control switch is kept closed.

In order to insure that the rockets will be delivered from the magazine into the firing position in the proper relation to the firing means, provision is made in the illustrated apparatus for controlling the position of each rocket axially of itself continuously as it advances down the outwardly and rearwardly directed slope of the magazine to the firing position and at the same time for insuring against any angular shifting of the rockets which would tend to cause them to be crowded against the end of the magazine so as to impede the feeding movement. To this end, and in the illustrated construction, the magazine is provided with a guide rail adapted to be engaged by the ends of the rockets, the rail being disposed obliquely with respect to the lower end of the magazine whereby the leading portion of each rocket adjacent to the rail advances into clear space and only the trailing portion of the end of the rocket engages the rail. Thus the advancing movement of a rocket consists of a rolling action (induced by the outward slope of the magazine) directed laterally of the rocket combined with a continuous sliding movement axially of the rocket (induced by the elevation of the magazine), the latter movement being under the control of and limited by the above-mentioned rail. On leaving the rail each rocket is positioned so that its firing terminals will engage the firing terminals in the firing circuit when the rocket falls into firing position.

The invention also make provision for the jettisoning of a mis-firing rocket. With this purpose in view, the illustrated apparatus comprises a movable launching way for supporting a rocket in firing position, the way being mounted for retraction from beneath the rocket whereby the latter is permitted to fall out of the launcher. In connection with this operation and as another feature of the invention, the illustrated apparatus also includes means for preventing feeding of another rocket into firing position when the above-mentioned launching way is retracted.

These and other features of the invention consist in certain devices, combinations and arrangements of parts, hereinafter described and claimed, the advantages of which will be apparent from the following description taken in

connection with the accompanying drawings, in which

Fig. 1 is a view in perspective of an illustrative rocket launcher embodying the invention as arranged for a port-side installation on an amphibious craft, and as viewed from an outboard position;

Fig. 2 is a side elevation of the launcher as viewed from an inboard position;

Fig. 3 is a rear elevation of the launcher at zero degrees elevation illustrating the jettisoning of a misfired rocket, and also illustrating certain features of a typical installation of the launcher on a craft, the hull, deck and coaming of which are indicated in broken lines;

Fig. 4 is a partial side elevation of the launcher as viewed from an outboard position;

Fig. 5 is a partial rear elevation of the launcher showing a rocket in firing position; and

Fig. 6 is a diagram of the firing circuit and certain parts of the launcher associated therewith.

The launcher has a frame 10 made in the form of a weldment and having end sections 12 of the shape shown in Fig. 3. Each end section is provided with a pair of lugs 14 which are fitted with studs 16. Either one of these sets of studs is adapted to be mounted upon a pivotal bracket 18 (Fig. 2) one of which is fixed to each side of the deck 19 of a craft so that either port and starboard installations, or both, may be made using launchers of identical construction. The end sections 12 are connected by a series of angle irons 20 which are arranged to extend longitudinally of the launcher. A series of angle irons 22 extend transversely between and are fixed to the angle irons 20, the arrangement of all the angle irons being such as to form a dihedral angle the upper side of which slopes downwardly outboard at an angle of about 30 degrees, the lower side being vertical. All these angles are covered by a continuous plate 24 (Figs. 1 and 3) which is perforated for lightness and forms the bottom and inboard side of a magazine adapted to hold rockets R.

The type of rocket illustrated herein comprises a cylindrical body B (Figs. 1 and 4) having tapered ends and a tail assembly consisting of a tube T containing the propellant, and a pair of contact bands C, D which are fixed to the rear end of the tube. The bands are insulated from each other and are electrically connected to the propellant in the tube T.

The ends of the magazine are formed by plates 26 and webs 28 which are bolted to the end sections 12. The top of the magazine is closed by a cover 30 which is bolted to the plates 26 and webs 28. At the inboard side of the magazine there is an opening (Fig. 1) between the cover 30 and the plate 24 through which rockets are loaded into the magazine. At its outboard side the magazine is bounded by a grill comprising a rectangular frame 32 (Figs. 1 and 4) having transverse members 34, the frame being fixed to the plates 26 in a vertical position.

The rockets roll through the magazine under the influence of gravity until they reach the grill and then descend vertically past a rotary gate 36 into the firing position which is that occupied by the lower rocket illustrated in Fig. 5.

The gate comprises two spiders 38 (Figs. 1 and 5) having three spokes to the ends of which are fixed three rods 40. The spiders are fixed to another rod 42 the ends of which extend beyond the spiders and are journaled in bearings 44 in

the end plates 26. Braces 46 connect the rod 42 with the rods 40 at their mid-points.

In order to prevent any upward movement of the rocket in firing position, or any such movement of the other rockets when one is fired, a series of pawls 48 are hinged on the transverse members 34 in such a position as to overlie and engage the upper part of that rocket above the one in firing position. The pawls are provided with springs 50 which first allow the pawls to yield as a rocket passes them, and then move the pawls into their operative position over the rocket as illustrated in Fig. 5.

The launcher is adjustable in elevation on the bracket 18 and is thus controlled by an elevating mechanism 52 (Fig. 3) which is operated by a hand crank 54.

The launcher will usually be elevated above the horizontal so that the rockets in the magazine tend to slide rearwardly thereof as they roll toward the firing position. This rearward sliding movement of the rockets is limited by a rail 56 (Figs. 3 and 4) which is fixed to the plate 24 slightly oblique to the end of the magazine, diverging rearwardly of the launcher away from the direction in which the rockets tend to roll. The effect of this arrangement is to keep the point of contact with the rail 56 of the rearmost band D on each rocket at the trailing side of the rocket. That is, the rockets tend, owing to their rolling action, to move away from the rail 56 rather than to be crowded against it, thereby insuring a free rolling action of the rockets. Further to insure against disalignment of the rockets during their feeding movement, the bottom plate 24 is provided with two rows of buttons 58 (Fig. 1) of rubber, or other suitable anti-slipping material, which are adapted to be engaged by the cylindrical portion of the body B of each rocket. It will now be apparent from the foregoing that the rockets are fed through the magazine in parallelism with each other with a motion which is a combination of a rolling action, induced by the downward and outward slope of the magazine, with a longitudinal sliding motion, induced by the downward slope of the magazine to the rear. During the vertical descent of each rocket into firing position, the band D engages another rail 58 (Figs. 4 and 5), which is a continuation of the rail 56, and is so mounted on the plate 24 as to permit a slight rearward movement of a rocket falling into firing position.

The rocket in firing position is supported by a launching way 60, the ends of which are attached to a pair of levers 62, each lever being pivoted to one of the plates 26 by means of a stud 64. The levers are held in their position as illustrated in Fig. 5, during the normal operation of the launcher, by mechanism which is also arranged to swing the levers and hence the launching way 60 from beneath the rocket in firing position to jettison it in case of a misfire.

This mechanism comprises a pair of toggle links 66, 68 associated with each of the levers 62 and a pair of operating rods 70, each rod at its lower end being connected to one pair of the links by a pin 72. The links 68 at each end of the launcher are fixed to the ends of a shaft 74 which is rotatably mounted on the plates 26 in bearings 76. The links 66 at their lower ends are pivotally connected to the levers 62 by pins 78. The upper ends of the operating rods 70 are slidably supported in bearings 80 (Figs. 1 and 3) which are fixed to the webs 28. Handles 82 are

adjustably fixed to the rods and normally are

yieldingly held against the bearings 80 by compression springs 84, the springs being interposed between the bearings 80 and stop collars 86 which may be adjustably fixed to the rods 70 so as to provide any suitable pressure in the springs 84.

Fixed to the plate 26 just below the rail 58 is a stop 88 (Figs. 3, 4 and 5) which, by engagement with the band D of the rocket in firing position, locates that rocket with its bands C, D in register with firing knives 90, 92. The knives extend through openings 94 in the plate 24 near the lower edge thereof and are mounted on heavy spring conductors 96, 98 respectively, the latter being housed in a box 100 fixed to the lower corner of the launcher at the inner side thereof. The knives 90, 92 are electrically connected in series with a source of power by conductors (Fig. 6) through a safety switch 102 (Figs. 1 and 5) which is fixed to the frame 32.

Fixed to the launching way 60 is a rail 104 having a beveled edge adapted to be engaged by the body B and bands C, D of the rocket in firing position, particularly to insure that the bands of the rocket will be held in contact with the firing knives 90, 92. In addition, the rocket is confined laterally between the rail 104 and the plate 24 at the inward side of the rocket for the purpose of directing the initial flight of the rocket. The rail 104 may be adjusted laterally to insure proper contact of the bands C, D with the firing knives, not only by adjusting the position of the handle 82 on the operating rod 70, but also by repositioning the launching way 60 with respect to the levers 62. To permit the latter adjustment, the launching way 60 has fixed to each end thereof a bracket 106 having elongated slots adapted to receive bolts 108 which are carried by the levers 62. The rail may thus be adjusted within the scope of the slots in the bracket 106. This adjustment is facilitated by set screws 110 which are threaded into lugs 112 fixed to the levers and which are adapted to bear against the outer sides of the launching way 60 adjacent to each end thereof. At a level slightly above that of the rail 104 the rocket in firing position is further guided laterally by another rail 114, the ends of which are fastened to the end plates 26.

In order to avoid short circuiting the bands C, D of the rocket in firing position, each of the rods 40 has a reduced portion 116 at each end which provides a clearance space between each rod and the forward band C. Similarly the launching way 60 is provided with a recess 118 which receives the band C with clearance; and the rail 104 is covered with a layer of insulating material (not shown) in the way of the bands C, D.

Assuming the magazine to be fully loaded, the rockets will lie side by side in contact with each other except in the case of the rocket in firing position and the succeeding one which, as illustrated in Fig. 5, are separated by the gate 36. The weight of that rocket above the one in firing position holds the gate against the latter rocket. Consequently, the gate and the way 60 cooperate to confine the rocket vertically and hence direct the rocket in its initial flight in accordance with the elevation of the launcher. With the gate 36 in this position its uppermost rod 40 engages a plunger 120 which holds the safety switch 102 closed. The plunger is mounted to slide vertically in a bearing 122 fixed to one end of the frame 32 and is normally urged away from the switch by a spring 124. Provision for adjustment of the plunger relatively to the switch is afforded by

lock nuts 126 which are threaded on the upper end of the plunger. The firing circuit will also include, at the firing station, a manually operated switch 127 (Fig. 6) which can be closed momentarily to fire the rocket in firing position and then opened before the succeeding rocket arrives in the firing position, whenever it is desired to operate the launcher by single-fire. When the switch 127 is held closed the launcher fires automatically by rapid fire, the firing being timed by the closing of the switch 102.

Immediately following the departure of the fired rocket from the launcher, the succeeding rocket falls into firing position causing the gate 36 to be rotated one-third of a revolution. At the beginning of each rotation of the gate the plunger 120 is released, opening the firing circuit. Thereafter no rocket can be fired until the switch 102 is again closed by the above described action of the gate 36 on the plunger 120. Hence, any danger of harm to the launcher or to the operating personnel which would result from firing a rocket which is disaligned with the launching way is prevented.

Up to the time when the last rocket in the magazine is to be fired the rocket next succeeding that in firing position causes the gate 36 to hold the switch 102 closed. However, when the last rocket in the magazine drops into firing position, the gate 36 is operated by a cam lever 128 to close the switch. This lever is pivoted at 130 to one of the end plates 26 and is normally urged in a clockwise direction by a spring 132 against a stop pin 134 carried by the end plate 26. The spring 132 is stretched between the upper end of the lever 128 and a clip 136 which is fastened to the plate 26. The lower arm of the lever 128 is crescent shaped, as illustrated in Fig. 5, and is adapted to be engaged by pins 138 which are fixed to an index plate 140 carried by the shaft 42 outside one of the plates 26 and just inside the adjacent lever 62.

Each time when a rocket descends into firing position the uppermost pin 138 engages the lever 128, and swings it in a counterclockwise direction thereby tensioning the spring 132. As soon as the pin passes a "dead center" position (where the greatest displacement of the lever 128 occurs) the tension in the spring 132 causes the lever 128 to drive the gate 36 into the position in which it is illustrated in Fig. 5 whereby the switch 102 is closed. This action of the lever 128 takes place whenever a rocket falls into firing position but is relied upon to close the switch 102 only when the last rocket in the magazine falls into firing position.

It will now be apparent that rockets may be fired from the illustrated launcher continuously in rapid succession so long as the firing circuit is kept closed at the firing station by means of the switch 127. The speed of firing is limited only by the time required for a fired rocket to leave the launcher and for the next succeeding rocket to drop into the firing position. Moreover, the firing of each rocket is effected automatically as soon as it has dropped completely into the firing position, the firing of the rocket being timed by the closing of the switch 102.

If the firing is interrupted by a rocket which misfires, that rocket is jettisoned by pulling one of the handles 82 so as to swing the launching way 60 from beneath the rocket in firing position, thereby allowing that rocket to fall out of the launcher. Whenever the launching way 60 is thus retracted, the gate 36 is immobilized in order

to prevent the other rockets in the magazine from falling out of it. To this end, when the lever 62 is swung outwardly, a lug 142 fixed to the inner side of the lever 62 which is adjacent to the index plate 140, moves into the path of the uppermost pin 138 on the plate. Accordingly, when a rocket is jettisoned the rotation of the gate 36 is stopped as soon as the uppermost pin 138 engages the lug 142; and the pin is not released by the lug until the launching way 60 has been moved far enough toward its normal position to catch the next rocket as it drops into firing position.

The elevating mechanism 52 has a base 144 (Figs. 1 and 3) adapted to be secured to a pad 146 by bolts 148 which pass through elongated slots in the base so as to permit lateral adjustment of the base with respect to the pad. The length of the slots is also sufficient to permit the base 144 to be slid inboard on the pad 146 far enough to be clear of the outer side of the craft when the launcher is removed from the craft. A shaft 150 is rotatably mounted in a bearing 152 which is integral with the base 144, and at its inboard end is provided with a socket 154 which receives the crank 54. A beveled gear 156 fixed to the shaft 150 meshes with another beveled gear 158, the latter gear being fixed to a shaft 160, the upper portion of which is threaded. The lower end of the shaft 160 is rotatably mounted in a bearing 162 which is mounted to swivel in a lug 164 formed integral with the base 144. The shaft 160 is threaded into a nut 166 having trunnions 168 which are rotatably mounted on a support 170. The support is at the common junction of a plurality of braces consisting of a pair of angle irons 172 which extend to the opposite lower inboard corners of the end sections 12, a second pair of angle irons 174 which extend to the opposite upper corners of the end sections 12, and another angle iron 176 which extends to the midpoint of the lower angle iron 20. It will now be evident that as the crank 54 is turned, the elevation of the launcher will be altered as it swings either up or down about the pivotal bracket 18.

Each bracket 18 comprises a pad 178 which is adapted to be fixed to the vehicle or craft on which the launcher is mounted. The pad has an inboard pair of lugs 180 which are bored to receive a shaft 182 on which a plate 184 is hinged. To the top of the plate 184 are fixed a pair of lugs 186 which are adapted to receive the studs 16 carried by the lugs 14 on the frame of the magazine. The plate 184 is normally held against any movement with respect to the pad 178 by a second shaft 188 which passes through the plate and also through a pair of lugs 190 which extend upwardly from the pad near its outboard edge. If the launcher is dismounted, the plate 184 may be moved to an inboard position, clear of the outer side of the craft, by removing the shaft 188 and swinging the plate inwardly towards the coaming.

A port-side installation of the illustrated launcher, as illustrated in Fig. 2, may be converted into a starboard-side installation by using the following procedure: the stop 88 which limits the rearward position of the rocket in firing position is removed from the left-hand end of the launcher (Fig. 2) and reinstalled on the other end of the launcher. Similarly the firing knives 90 and 92 are to be reinstalled in a box 192 similar to the box 100. It is also to be understood that all features of the launcher relating to the guiding of the rockets into the firing position (such as the rails 56 and 58) which have

been described as embodied in one end of the launcher are also duplicated in the other end of the launcher. The launcher is of such length as to cause the bodies B of the rockets to engage both rows of buttons 57 regardless of which of the rails 56 is engaged by the rockets. Looking at Fig. 2 as an starboard installation of the launcher, its right-hand end will be swung down to permit the right-hand studs 16 to be assembled with the right-hand pivotal bracket 18 (broken lines), it being understood that any craft intended to carry both port and starboard installations, the craft will be provided on each side with a pivotal bracket 18 and a pad 146 to receive the base 144 of the elevating gear 52.

The use and operation of the illustrated launcher will now be briefly summarized.

Let it be assumed that the launcher has been completely loaded, one rocket, the lower one, which rests upon the launching way 60, being in the firing position. At this time the contact bands C, D of the rocket in firing position are engaged by the firing knives 90, 92, respectively, and the switch 102 is held in its closed position by the plunger 120 which has been actuated by the gate 36. The rocket in firing position will be fired immediately upon the closing of the switch 127 which is under the control of the operator at the firing station. If this switch is held closed, the entire supply of rockets in the magazine will be fired in rapid succession, the firing of each rocket being timed by the operation of the switch 102 in the following manner: As soon as a rocket in firing position is fired, the gate 36 is rotated in response to the falling movement of the next rocket into the firing position. During the initial rotation of the gate, the upper pin 138 on the index plate 140 engages the lever 128 causing the lower end of this lever to be swung upwardly and inboard of the launcher against the tension of the spring 132. This rotation of the gate and index plate 140 is continued under the driving effect of the rocket falling into firing position until that pin 138 which engages the lever 128 has moved past its dead center position. During the final movement of the rocket into firing position, when it has no tendency to rotate the gate 36, the lever 128 bears upon the pin 138 and causes the rotation of the gate to be continued until the rod 40 above the rocket in firing position is brought into engagement therewith. At the end of each such rotative movement of the gate, one of its rods 40 engages the plunger 120, lifts it, and thereby closes the switch 102. Thus, each rocket is fired automatically upon its arrival in the firing position. Ordinarily, the gate is driven toward the end of each movement by the weight of the rocket next to the leading rocket, as well as by the lever 128; but when the last rocket in the launcher moves into the firing position, the final rotation of the gate which closes the switch 102 is derived from the action of the lever 128 alone.

If the firing should be interrupted by the failure of a rocket to fire, that rocket can be jettisoned by pulling upon the handle 82 which causes the launching way 60 to be retracted from beneath the misfired rocket as illustrated in Fig. 3. The rocket in firing position is thus permitted to drop out of the launcher, but the succeeding rockets are prevented from advancing toward the firing position by the gate 36 which is immobilized whenever the launching way is moved out of its operative position by the engagement of

the lug 142 on the lever 62 with the upper pin 138 on the index plate 140.

Having described my invention, what I claim as new and desire to secure by Letters Patent of the United States is:

1. A rocket launcher comprising a magazine, a launching way arranged to support a rocket in firing position, said magazine being inclined downwardly toward said launching way whereby rockets are fed by gravity into firing position from said magazine, means for firing a rocket when in firing position, said means comprising a firing circuit having terminals arranged to be engaged by corresponding terminals on the rocket in firing position, a switch, and means actuated by a rocket during its movement into firing position for closing said switch.

2. A rocket launcher comprising a sloping magazine adapted to receive a plurality of rockets and having a movable launching way onto which rockets are fed by gravity into firing position, a gate for controlling the feeding movement of the rockets into firing position, means for retracting said launching way from beneath a rocket in firing position to jettison that rocket, and connections between said means and said gate constructed and arranged to immobilize said gate when said way is retracted whereby feeding movement of the rockets into firing position is prevented.

3. A rocket launcher comprising a sloping magazine adapted to receive a plurality of rockets and having a movable launching way toward which the rockets are fed by gravity from said magazine, said way being mounted and arranged to support a rocket in firing position, a gate for controlling the feeding movement of the rockets into firing position, operator-controlled means constructed and arranged to retract said way from beneath the rocket in firing position whereby that rocket is jettisoned, and means for simultaneously immobilizing said gate whereby feeding movement of the succeeding rockets is prevented while said way is retracted.

4. A rocket launcher comprising a magazine adapted to receive a plurality of rockets, a launching way onto which the rockets are fed from said magazine, said way being arranged to support a rocket in firing position, a gate constructed and arranged to separate the rocket in firing position from the next succeeding rocket, means for retracting said way from beneath the rocket in firing position to jettison that rocket, and connections between said means and said gate for immobilizing said gate when said way is retracted thereby to prevent feeding movement of the said next succeeding rocket.

5. A rocket launcher comprising a sloping magazine adapted to receive a plurality of rockets, a launching way toward which the rockets are fed by gravity from said magazine, said way being arranged to support a rocket in firing position, a rotary gate having a plurality of spacing bars, successive bars being arranged to receive therebetween the rocket next succeeding that in firing position, means for moving said launching way from beneath a rocket thereon in firing position to permit the rocket to fall off said way, and a stop actuated by said means for preventing rotation of said gate until said launching way has been returned to its original position.

6. A rocket launcher comprising a magazine adapted to receive a plurality of rockets, a launching way toward which rockets in said magazine are fed by gravity, said way being arranged

to support a rocket in firing position, said way being mounted to swing from beneath a rocket thereon in firing position, operator-controlled mechanism for operating said launching way to jettison a rocket in firing position, a freely rotatable gate adapted to be rotated by the movement of a rocket into firing position from said magazine, and means for preventing said gate from rotating when said way is swung, said means comprising an index plate associated with said gate, a stop mounted for movement into the path of said plate, and connections between said mechanism and stop for moving said stop into its operative position when said way is swung away from beneath a rocket in firing position.

7. A rocket launcher comprising a magazine adapted to hold rockets, a launching way on which a rocket is supported in firing position, a movable gate arranged to be operated by the movement of a rocket from said magazine into firing position, a firing circuit including a terminal arranged to be engaged by a corresponding terminal on the rocket in firing position and a switch, a member for operating said switch disposed in the path of movement of said gate, and means for imparting a limited movement to said gate beyond that imparted to said gate by the movement of a rocket into firing position, whereby said gate is caused to actuate said operating member to close said firing circuit.

8. A rocket launcher comprising a magazine adapted to hold rockets, a launching way on which a rocket is supported in firing position, a rotary gate arranged to be rotated by a rocket in its movement from said magazine into the firing position, a firing circuit including a switch arranged to be opened and closed by said gate, and a yieldingly mounted lever constructed and arranged to be moved first in one direction and to be energized by said gate and then to move in the opposite direction to drive the gate beyond the position into which it was driven by the rocket in firing position whereby said switch is operated by said gate to close the firing circuit.

9. A rocket launcher comprising a magazine adapted to receive a plurality of rockets, a gate mounted for rotation and adapted to be driven by a rocket in its movement from said magazine into firing position, said gate comprising a plurality of bars one of which separates that rocket in firing position from the next succeeding rocket and prevents the feeding of the latter rocket until that in the firing position has been fired, a firing circuit including a terminal arranged to be engaged by a corresponding terminal on the rocket in firing position, and a switch operated by said gate for successively opening and closing said firing circuit during the movement of the said next succeeding rocket into firing position.

10. A rocket launcher comprising a sloping magazine adapted to receive a plurality of rockets side by side parallel to each other, means for supporting a rocket in firing position, said means being mounted for retractive movement from beneath the rocket in firing position to jettison that rocket, means operable in synchronism with the retractive movement of said last-mentioned means for preventing the movement of the next succeeding rocket from said magazine toward the firing position, and means for firing the rocket in firing position comprising a firing circuit including a terminal adapted to be engaged by a corresponding terminal on the rocket in firing position.

11. In a rocket launcher, a sloping magazine adapted to receive a plurality of rockets disposed side by side parallel to each other, the base of said magazine having an anti-slipping surface for maintaining the rockets in parallelism with each other as they roll through the magazine, and a guide rail mounted obliquely at one end of said magazine whereby the width of the base of the magazine constantly increases as the rockets advance through said magazine and only the trailing portions of the ends of the rockets engage said rail.

12. In a rocket launcher, a sloping magazine adapted to receive a plurality of rockets disposed side by side parallel to each other, the base of said magazine having spaced anti-slipping tracks thereon and arranged to be engaged by the cylindrical body portion of each rocket whereby the rockets are maintained in parallelism with each other as they roll through said magazine, and a guide rail mounted at one end of said magazine, said rail being adapted to be engaged by

the tails of the rockets, said rail also being arranged to diverge from the direction of rolling motion of the rockets whereby only the trailing portions of the said tails engage said rail.

WILLIAM V. GOODHUE.
